UNITED STATES PATENT OFFICE

CHARLES N. MONTEITH, JOHN KYLSTRA, AND ROBERT J. MINSHALL, OF SEATTLE, WASHINGTON, ASSIGNORS TO BOEING AIRPLANE COMPANY, OF SEATTLE, WASHINGTON, A CORPORATION OF WASHINGTON

DESIGN FOR A PURSUIT AIRPLANE

Application filed October 7, 1932. Serial No. 45,253. Term of patent 3½ years.

To all whom it may concern:

Be it known that we, CHARLES N. MONTEITH, JOHN KYLSTRA, and ROBERT J. MINSHALL, citizens of the United States, residing at Seattle, in the county of King and State of Washington, have invented a new, original, and ornamental Design for Pursuit Airplanes, of which the following is a specification, reference being had to the accompanying drawings, forming part thereof.

Figure 1 is a plan view of the airplane, showing our new design.

Figure 2 is a front elevation of the same in flight.

Figure 3 is a side elevation of the airplane in flight.

We claim:

The ornamental design for a pursuit airplane, as shown.

Signed at Seattle, King County, Washington, this 28th day of September, 1932.

CHARLES N. MONTEITH.

JOHN KYLSTRA.

ROBERT J. MINSHALL.
